DESIGN FOR A SINK FIXTURE

John M. Little, Toledo, Ohio

Application October 9, 1946, Serial No. 133,853

Term of patent 14 years

(Cl. D91—3)

To all whom it may concern:

Be it known that I, John M. Little, a citizen of the United States and a resident of Toledo, Lucas County, Ohio, have invented a new, original, and ornamental Design for Sink Fixture, of which the following is a specification, reference being had to the accompanying drawing, forming a part thereof, in which—

Fig. 1 is a front view of a sink fixture, showing my new design;

Fig. 2 is a top view; and

Fig. 3 is an end view thereof.

I claim:

The ornamental design for sink fixture, substantially as described and shown.

JOHN M. LITTLE.
